ATTORNEY

UNITED STATES PATENT OFFICE.

FRANK O. HOAGLAND, OF BRIDGEPORT, CONNECTICUT, ASSIGNOR TO PRATT & WHITNEY COMPANY, OF NEW YORK, N. Y., A CORPORATION OF NEW JERSEY.

SNAP GAUGE.

Application filed September 14, 1926. Serial No. 135,446.

This invention relates to gauges and in particular to an outside dimensional gauge having opposed adjustable anvils.

An object of the present invention is to provide improved adjusting means for an anvil of a gauge adapting the anvil to be positively adjusted in opposite directions relative to the gauge frame.

Another object of the invention is to provide screw threaded means for adjusting the anvil of a gauge having threaded portions of right and left hand.

One feature which is advantageous is that the right and left threaded member engages internal threaded portions formed respectively in the frame and anvil.

Another object of the invention is to provide improved rotatable cam locking means for the anvil enabling the anvil to be locked in any adjusted position.

With the above and other objects in view my invention consists in the features of construction and operation set forth in the following specification and illustrated in the accompanying drawing.

In the accompanying drawing annexed hereto and forming a part of this specification, I have shown my invention embodied in a snap gauge having a single pair of opposed adjustable anvils but it will be understood that the invention can be otherwise embodied and that the drawing is not to be construed as defining or limiting the scope of the invention, the claims appended to this specification being relied upon for that purpose.

In the drawing:

Figure 1 is a side view of a complete snap gauge having the improved anvil adjusting and locking means, one side of the frame being sectioned to more clearly show the invention.

Fig. 2 is a sectional view taken upon the line 2-2 of Fig. 1.

Fig. 3 is a separate view of the oppositely threaded adjusting member for the anvil, and

Fig. 4 is a separate view, on an enlarged scale, of the rotatable cam locking member for the anvil.

In the above mentioned drawing I have shown but one embodiment of the invention which is now deemed preferable, but it is to be understood that changes and modifica-

tions may be made within the scope of the appended claims without departing from the spirit of the invention.

Briefly, and in its broadest aspect, my invention comprises the following principal parts: first, a frame substantially of U form; second, anvils adjustably positioned within the frame and movable toward or from each other; third, a member having oppositely threaded portions adapted to engage internal threads formed respectively in the frame and anvil; and fourth, a rotatable cam member disposed transversely to the anvil and adapted to clamp the anvil in any adjusted position.

Referring more in detail to the figures of the drawing a gauge embodying the invention is shown having a frame 10 of U form of any desired distance between the arms. At the ends of the arms of the frame 10 are mounted anvils 11 preferably having heads 12 at their inner ends. The anvils 11 are in alignment with each other and one or both may be provided with the improved adjusting and locking means. As shown in Figs. 1 and 2 the anvils 11 are adapted to slide within cylindrical openings in the frame 10.

In order to adjust an anvil 11 it is provided with internal threads 13 extending axially of the anvil. In engagement with these threads 13 are threads 14 on the smaller diameter portion of the adjusting member 15. The larger diameter portion of this member 15 is provided with threads 16 adapted to engage threads 17 formed internally in the cylindrical opening in the frame 10 for the anvil 11. The threaded portions 14 and 16 on the adjusting member 15 are of opposite hand. It will be seen therefore that rotation in one direction of this member 15 will positively move the anvil 11 in one direction and rotation of the member 15 in the opposite direction will oppositely move the anvil 11. To rotate the member 15 its outer end is slotted as shown at 18.

The clamping means for the anvil 11 comprises a rotatable member 19 freely rotatable within a transverse opening in the frame 10 intersecting the opening for the anvil 11. At the ends of this member 19 are cylindrical portions 20 adapted to engage the walls of the transverse opening within which the member 19 is mounted. Centrally of the

member 19 the surface is cam or spirally shaped, as shown at 21, so that by rotating the member 19 this surface can be brought into contact with a plane surface 22 formed 5 along one side of the anvil 11. To rotate the clamping member 19 one end may be slotted as indicated at 23.

From the above description it will be seen that by rotation of the adjusting member 15 10 the position of the anvil 11 relative to the frame 10 may be positively adjusted in either direction. Also that when the anvil 11 has been adjusted to the desired position it may be clamped in fixed position by means of the 15 clamping member 19. As the cam member 19 is at all times closely adjacent the flattened portion 22 of the anvil 11 the anvil is prevented from rotating while being adjusted longitudinally.

20 What I claim is:

1. A snap gauge comprising in combination, a frame having internal threads formed therein, an anvil slidably mounted therein having internal threaded portions, an adjusting member positioned within the frame and having threaded portions of opposite hand engaging respectively the internally threaded portions in the frame and in the anvil,

and means to lock the anvil in any adjusted position.

2. A snap gauge comprising in combination, a frame, an anvil slidably mounted therein, an adjusting member positioned within the frame and disposed in alignment with the anvil, threaded portions on said adjusting member of opposite hand, internally threaded portions on said frame and anvil adapted respectively to engage the threaded portions of said adjusting member, and means to lock the anvil in any adjusted position.

3. A snap gauge comprising in combination, a frame, an anvil slidably mounted therein, an adjusting member positioned within the frame and disposed in alignment with the anvil, threaded portions on said adjusting member of opposite hand, internally threaded portions on said frame and anvil adapted respectively to engage the threaded portions of said adjusting member, and rotatable cam means to lock the anvil in any axial adjusted position.

In testimony whereof, I hereto affix my signature.

FRANK O. HOAGLAND.
